UNITED STATES PATENT OFFICE.

KARL HAMPEL, OF DETROIT, MICHIGAN.

DETONATING DEVICE.

1,425,198.

Specification of Letters Patent.

Patented Aug. 8, 1922.

Application filed October 8, 1920. Serial No. 415,650.

To all whom it may concern:

Be it known that I, KARL HAMPEL, a citizen of Jugo-Slavia, residing at Detroit, in the county of Wayne and State of Michigan, have invented certain new and useful Improvements in Detonating Devices, of which the following is a specification, reference being had therein to the accompanying drawings.

10 The primary object of my invention is to provide a detonating device by which a fulminate wafer, cap or explosive mixture may be safely exploded by juveniles, and the device may take the form of a toy dart, pin 15 wheel or mallet, either of which will afford considerable amusement to juveniles and in the form of a dart requires some skill when aimed and projected at a target.

Another object of this invention is to provide as a new article of manufacture a wafer 20 or cap holder which may be manufactured at a comparatively small cost and safely used in connection with the device.

The above and other objects may be attained by a mechanical construction that will be hereinafter described and then claimed, and reference will now be had to the drawing wherein—

Figure 1 is a perspective view of the preferred form of toy dart;

Fig. 2 is an enlarged elevation of a portion of the same, partly broken away and partly in section;

Fig. 3 is a side elevation of a modified 35 form of dart, partly broken away and partly in section;

Fig. 4 is a side elevation of a mallet that may be used as a detonating device, and

Fig. 5 is a side elevation of a cap holder, 40 partly broken away and partly in section.

The invention in its broadest aspect involves a carrier socket, and holder and by reference to Fig. 1 the carrier takes the form of a stick or dart 1 having a distal portion 45 provided with vanes 2 which may be of any number and suitably attached to the end of a stick, for instance, by mounting the vanes in slots 3 of the stick and securing the same therein by staples 4, pins or other fastening means. The vanes constitute means for causing the stick to travel in a direction in which it is projected, for instance, maintaining the stick plumb when descending by gravity. The opposite end of the carrier 55 has a reduced end 5 to receive a socket 6,

which takes the form of a split sleeve mounted on the reduced end 5 of the stick 1 and projecting therefrom. In the socket 6 is a weight or heavy body 7 against the reduced end 5, the weight lending a heavy end to the 60 stick when falling, besides providing an abutment within the socket. The socket may be secured to the weight or to the reduced end 5 by depressing a portion of the socket, as at 8, although other means may be 65 resorted to in maintaining the socket constantly in engagement with the stick.

The holder comprises a short body or stick 9 adapted to fit in the socket 6 against the weight or abutment 7 therein and the holder 70 is adapted to be detachably held during flight of the dart so that its outer end will be exposed for impact against the wall, the ground, a target, or any surface at which the dart is projected.

Suitably secured to the outer end of the holder 9 is a fulminate wafer, cap or explosive mixture 10, and as shown in Figs. 1 to 4 inclusive the outer end of the holder may have a cavity 11 to receive a portion of 80 the cap or explosive mixture. The cap or explosive mixture may be held in engagement with the holder by a suitable adhesive or it may be otherwise connected thereto, for instance, as shown in Fig. 5 where the outer 85 end of the holder has a concave seat 12 on which may be molded or deposited a quantity of an explosive mixture, so that the holder will have a head, somewhat similar to a match.

In Fig. 3 the carrier stick 13 has a simple form of pin wheel 14 as a substitute for the vanes 2, and the opposite end of the carrier 6 is bored out to provide a socket 15 which is bifurcated, as at 16, so that the side walls 90 of the socket will be somewhat yieldable and will frictionally grip a holder placed therein.

In Fig. 4 the carrier takes the form of a hammer or mallet 17 having its blow head 18 provided with a recess 19 in which is mounted a socket 20 for a holder 21, the socket being in the form of a split sleeve adapted to be sprung to frictionally grip the holder when inserted therein. In this instance the blow head 18 serves as an abutment for the holder 100 21 and the hammer or mallet may be manipulated to detonate the cap of the holder 21 by percussive force. This form of detonating device may be advantageously used during various celebrations where limited space 110

would prevent the throwing of the darts shown in Figs. 1 and 3.

With the holders 9 made of an inexpensive material a multiplicity of these holders can be furnished with each carrier, so that a child will have sufficient ammunition for producing a multiplicity of detonations, the loudness of which depends on the character of the explosive mixture. In either form of the device the detonator is practically harmless, and it is obvious that the carrier and its appurtenant parts may be finished to present a neat and attractive appearance which will appeal to children.

15 While in the drawing there are illustrated the preferred embodiments of my invention, it is to be understood that the structural elements are susceptible to such changes in size,

shape and manner of assemblage as fall within the scope of the appended claim. 20

What I claim is:—

A detonating device comprising a carrier having a reduced cylindrical end, a split sleeve socket carried by the reduced end of said carrier and protruding therefrom, a 25 weight in said socket against the reduced end of said carrier, said socket having a depressed portion engaging said weight, and a detachable cap holder in said socket against said weight and protruding therefrom. 30

In testimony whereof I affix my signature in presence of two witnesses:

KARL HAMPEL.

Witnesses:

OTTO F. BARTHEL,

ANNA M. DORR.
